No. 37,494.

Patented July 18, 1905.

UNITED STATES PATENT OFFICE.

GUSTAVE FOX, OF CINCINNATI, OHIO.

DESIGN FOR A PENDANT.

SPECIFICATION forming part of Design No. 37,494, dated July 18, 1905.

Application filed June 15, 1905. Serial No. 265,458. Term of patent 7 years.

To all whom it may concern:

Be it known that I, GUSTAVE Fox, a citizen of the United States, residing at Cincinnati, in the county of Hamilton and State of Ohio, have invented a new, original, and ornamental Design for a Pendant, of which the following is a specification, reference being had to the accompanying drawing, forming a part hereof, and which represents a plan view of an ornamental pendant, showing my new design.

I claim—
The ornamental design for a pendant as shown.

GUSTAVE FOX.
